PERCUSSION-FUSE.

1,062,810.

Specification of Letters Patent. Patented May 27, 1913.

Application filed May 11, 1912. Serial No. 696,730.

To all whom it may concern:

Be it known that I, KARL WIESER, residing at Bredeney, Germany, a subject of the Emperor of Germany, have invented a certain new and useful Improvement in Percussion-Fuses, of which the following is a specification.

This invention relates to percussion fuses in which all the moving parts are located within the fuse housing and the object of the invention is to provide a fuse of this kind which is distinguished by great sensitiveness and by accurate action not only when the projectile strikes with the point but also when it strikes with the base. In accordance with the present invention this object is attained in this manner, that one of the parts carrying the ignition means is actuated by an ignition spring which is held back by a latch, and that a percussion hammer is utilized for its release. This percussion hammer can move in several directions on account of its inertia; after being released from a safety device provided for it, and the hammer is so constructed that it will operate the latch in whatever direction it moves.

So-called contact fuses for sea mines are already known, that is to say fuses which are provided with a percussion hammer effecting the ignition and extending beyond the outer surface of the fuse, wherein one of the parts carrying the ignition means is actuated by an ignition spring which is held back by a latch. This latch may be released either automatically when a ship hits the mine by the effect of the impact on the percussion hammer; or by hand-pull on the percussion hammer from a distant point. It has also been proposed to use such fuses for torpedoes. In the latter case, the release of the latch can naturally only be accomplished by impact with the percussion hammer.

The object of the fuse of the present invention differentiates from that of the known fuses therein, that the inertia of the percussion hammer is utilized to produce a projectile fuse, which is always set automatically in action, whether the impact of the projectile be made by the point or the base.

One embodiment of the invention is illustrated in the accompanying drawings where

a base percussion fuse has been shown, and whereof—

Figure 1 is a section along the longitudinal axis of the fuse; Fig. 2 a section on line 2—2 of Fig. 1 seen from the left; Fig. 3 a section on line 3—3 of Fig. 1 seen from above and Fig. 4 a section on line 4—4 of Fig. 2 seen from above.

The fuse body consists of two hollow parts A and B connected by screw threads. The forward hollow part B has two chambers B¹ and B² divided by a partition b³ (compare Fig. 2) and is closed up by a screw plug C, which contains the fulminate c¹. The chamber B¹, which is formed by two bores, offset, stepwise, contains a cup-shaped percussion hammer D, which reaches forward into the bore c² of the screw plug C. The percussion hammer D is actuated by a spring E, which abuts with one end against a washer F lying on the partition b³, and tends to push the percussion hammer in the direction of piercing the fulminate c¹. The percussion hammer D is held in its transport position, illustrated in the drawing, by means of two double-armed pawls G, which are adapted to oscillate on pins g¹ within apertures B⁴ of the hollow part B, the axes of which pins run at right angles to the longitudinal axis of the fuse. For this purpose the pawls G are at one end provided with toes g² which engage with an annular flange d² on the percussion hammer D. The other ends of the pawls G carry toes g³ which simultaneously bear against a collar h¹ on a sliding bolt H. This sliding bolt H extends with its forward end into the chamber B² of the hollow part B and reaches with its reinforced rear end h² into a bore a¹, closed on the outside, in the bottom of the hollow part A, and this sliding bolt H is displaceable in both directions of the longitudinal axis of the fuse.

To secure the sliding bolt H in transport position and against rearward displacement in firing, a plurality of dogs J, see particularly Fig. 4, are arranged in well known manner. These dogs J actuated by the centrifugal force automatically release the sliding bolt H after the firing, but in their operative position they engage in a groove h³ of the sliding bolt H. The pawls G are so constructed that the ends thereof that carry the toes g² tend to swing outward ac-

tuated by the centrifugal force, so that the toes g^3 with a certain pressure impinge the collar h^1 of the sliding bolt H. This pressure is so calculated that the friction caused thereby is able to exercise only a small resistance against any displacement of the sliding bolt H. When the projectile therefore hits a target, only a slight impact either at the point or the base will be necessary to cause the sliding bolt H to be displaced on account of its inertia either toward the point or toward the base of the projectile, as the sliding bolt H is only held by the friction from the toes g^3 after the swinging out of the dogs J. In either case the collar h^1 of the sliding bolt H will disengage the toes g^3 . The ends of the pawls G that carry the toes g^2 will then fly apart, actuated by the centrifugal force, so that the toes g^2 will slide off the collar d^2 of the percussion hammer D, thereby setting free the percussion hammer D, which thereupon by means of the spring E will drive its firing pin d^4 into the fulminate c^1 thus causing the ignition.

I claim:—

1. In a percussion fuse, the combination with ignition means comprising a fulminate and a firing pin; a percussion hammer carrying one of said ignition means, a firing spring tending to drive the hammer in the direction to fire said ignition means; arresting means for said percussion hammer, normally holding said percussion hammer retracted against said firing spring, a releasing bolt engaging said arresting means and movable on impact in various directions only by the action of inertia, said bolt being adapted to release said arresting means when moving in any direction, and a casing completely inclosing the percussion hammer, the firing spring, the arresting means and said releasing bolt.

2. In a percussion fuse having a main body inclosing all the moving parts of the fuse, a fulminate seated in said main body; a percussion hammer; a firing pin on said percussion hammer; a spring acting between the main body and the percussion hammer to drive the latter against the fulminate; arresting means normally holding said per-

ussion hammer in a retracted position, said arresting means comprising a flange on said percussion hammer, pawls mounted in said main body to oscillate in radial planes through the longitudinal axis of the fuse, each of said pawls having a long and a short arm, the long arms of the pawls normally engaging said flange; a sliding bolt, mounted to slide axially in both directions in the main body, a collar on said sliding bolt normally in engagement with said short arms of the pawls; releasing means for said bolt actuated by the centrifugal force.

3. In a percussion fuse having a main body inclosing all the moving parts of the fuse, a fulminate seated in said main body; a percussion hammer; a firing pin on said percussion hammer; a spring acting between the main body and the percussion hammer to drive the latter against the fulminate; arresting means normally holding said percussion hammer in a retracted position, said arresting means comprising a flange on said percussion hammer, pawls mounted in said main body to oscillate in radial planes through the longitudinal axis of the fuse, each of said pawls having a long and a short arm, the long arms of the pawls normally engaging said flange; a sliding bolt, mounted to slide axially in both directions in the main body, a collar on said sliding bolt normally in engagement with said short arms of the pawls; releasing means for said arresting means, comprising a plurality of dogs fulcrumed to swing in a plane at right angles to the longitudinal axis of the fuse, a groove in said sliding bolt normally engaging said dogs; the dogs swinging out of said groove actuated by the centrifugal force leaving the sliding bolt free for displacement in any axial direction on impact, whereby said pawls will be free to release said hammer, the spring actuated hammer thus striking the fulminate.

The foregoing specification signed at Barmen, Germany, this 25th day of April, 1912.

KARL WIESER. [L.S.]
